UNITED STATES PATENT OFFICE.

RUBEN C. M. HASTINGS, OF COLUMBUS, OHIO, ASSIGNEE TO INTERNATIONAL TELEPHONE COMPANY, OF COLUMBUS, OHIO.

SELECTIVE TELEPHONE SYSTEM.

1,392,762.

Specification of Letters Patent.

Patented Oct. 4, 1921.

Application filed November 28, 1913, Serial No. 803,596. Renewed November 6, 1920. Serial No. 422,364.

To all whom it may concern:

Be it known that I, RUBEN C. M. HASTINGS, a citizen of the United States, residing at Columbus, in the county of Franklin and State of Ohio, have invented a new and useful Selective Telephone System, of which the following is a specification.

The present invention relates to improvements in selective telephone systems, one object of the present invention being the provision of a system, in which peculiar mechanisms are disposed in all substations, whereby the substations may be shunted from the line, and also whereby the called substation may be signaled through the call-up alarm, whether the receiver is upon or off the hook, there being provided in the present system automatic shunting, receiver hook locking, selecting and signaling mechanisms to control the various elements and instruments employed, the selecting being entirely under the supervision and control of the exchange operator as in my former Patent No. 1,061,285 granted to me May 13, 1913; the selecting key in the present case being identical with the structure set forth in my U. S. Patent No. 1,061,286 granted to me May 13, 1913.

A further object of the present invention, is the provision of a selecting disk embodying some of the features of the selecting disk shown in my U. S. Patent No. 1,062,004, granted to me May 20, 1913, such disk constructed and arranged, as to control the shunting switch and other switches controlled by the shunting switch to permit of the signaling of the called substation whether the receiver is upon or off the hook, and also to control such substations regardless of the position of the receiver, the same providing a means whereby a subscriber at a substation intending to steal cannot communicate with the exchange, but can be communicated with by the exchange so as not to penalize a calling subscriber when such stealing substation is desired by a person at a calling substation.

A still further object of the present invention is the provision of a mechanism at the substation, whereby a subscriber, who attempts to steal a conversation is automatically shunted from the line, and yet at the same time is placed in such a position as to be called or connected by the exchange station for the proper connection with a calling subscriber, such shunted substation being pre-

vented from calling or talking to any station except the exchange station, but being in a position to be talked to by the exchange operator, thus permitting and making it possible for the exchange operator to notify such stealing substation to place the receiver upon the hook and thus establish the proper connection with the line.

A still further object of the present invention is the provision of a novel form of automatic shunt or lock out device, in which the control of the various contacts or switches are placed directly under the influence of a spring and electromagnetically actuated mechanism, which in turn is operated through the selecting key disposed at the exchange station.

A still further object of the invention is the provision of a visual, non-audible, busy signal adapted to be displayed at the substations so as to notify at a glance whether or not the line is in position for calling the exchange station, the same being preferably a small low voltage lamp circuit connected to a low voltage battery in each substation and having a switch in circuit controlled by the mechanism at such substations.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—

Figure 1 is a diagrammatic view showing an exchange and a single substation installed according to and embodying the present invention, magneto machines being used in the substations for controlling the signal at the exchange station, the parts being in normal or zero position so that any one of the substations can call the exchange.

Fig. 2 is a similar view to Fig. 1 showing the parts in position when a calling substation is communicating with the exchange station, the medium dark lines indicating the flow of current to the line and the signaling device at the exchange station.

Fig. 3 is a view similar to Fig. 1 showing the use of an alternating current call-up alarm generator installed at the exchange

station, and whereby the signal at the exchange station is operated due to the removal of the receiver from the hook in any one of the substations:

- 5 Fig. 4 is a similar view to Fig. 3 showing the parts in the position they assume when a calling substation is connected to the exchange with the receiver from the hook and the signal device at the exchange operated,
 10 the medium dark lines indicating the flow of signal current to operate the signal at the exchange station.

Fig. 5 is a view in vertical section and partly in elevation of a desk instrument outfit, showing the present substation controlling mechanism located and carried within the base thereof.

15 Fig. 6 is a top plan view of the substation controlling mechanism taken on line 6-6 of Fig. 5.

20 Fig. 7 is a section taken on line 7-7 of Fig. 5.

25 Fig. 8 through 17 are diagrams of the periphery of the switch controlling disk in various positions.

25 Figs. 18, 19, 20 and 21 are detail views of various positions of the controlling device and shunt switch.

30 Fig. 22 is a detail perspective view of the switches controlled by the receiver hook and its rod.

Fig. 23 is a sectional view of the base of the desk instrument showing the visual busy signal lamp.

35 Figs. 24 and 25 are enlarged detail views of the mechanical means for placing the shunt switch in shunt operating position by means of the receiver hook rod.

40 Figs. 26 and 27 are similar views of a modification.

In order to more fully understand the present invention, the detailed description of the controlling disks 36 and 37 and their operation, and the shunt switches or contacts 38 and 39 will be set forth. The disk 36, which is the main disk for controlling the shunt switch and the other switches therefrom, is provided with the three ridges *a*, *b* and *c*, and two grooves 54 and 58, this disk and the switch 38-38 constitutes the shunting means to shunt the substation S from the line L-L' when necessary, being operated from the exchange through the instrumentality of the selecting key K at the exchange station E and providing a means for automatically shunting from the line, the uncalled substations and connecting for communication the called substation with the calling substation for a private or non-interfering conversation, the operation of the disk 36, as will presently appear, being completely and solely under the control of the selecting key from the exchange station.

More clearly set forth the construction 65 and operation, the description will follow

the operation in starting with the asking by a calling substation of the exchange, and the connection by the exchange of a called substation. To therefore clearly describe the operation, we will presuppose that the subscriber at substation No. 1 is calling for subscriber at substation No. 5, all of the disks 36 at this time being at what is termed zero position, with all pins 38' carried by the shunt contacts 38 disposed at position 60 and as clearly illustrated in Figs. 8 and 9 of the diagrams of the periphery of such disks 36. Thus the ridge *a* at such point will engage the pin 38' and hold the shunt contacts downwardly against the tension of the spring 41', the detailed construction and arrangement of which will presently appear. The shunt contacts 38 and 39 at this position *a'* in all substations are separated and open and therefore all substations are connected to the line for communication with the exchange station E.

In the diagram as shown in Figs. 1 and 2, the magneto machine A is operated at the substation No. 1. Before the receiver R is removed from the hook 25, the signal 9 at the exchange is energized by operating the magneto A to indicate to the exchange that a substation is calling. The exchange operator inserts the answering jack plug 1 in the socket 14, and thus is connected to the line for responding to the signal of the calling substation, and such calling substation as before assumed asks to be connected with substation No. 5.

100 The selecting key, as described in my U. S. Patent No. 1,061,286, above referred to, is manipulated as therein set forth to select the instrument No. 5 and thus automatically, this action as will presently appear, causes the closure of a circuit to the call-up alarm 81 in substation No. 5 and consequently the signaling of such substation, all disks 36 in the various substations being actuated by the step-by-step motion imparted to the 110 shaft 35 of the disks 36 and 37 through the instrumentality of the electro magnet 29 which is connected at all times in circuit with the line L-L', the circuit of which will be described in full later on. Thus all of the disks 36 in every substation are caused to automatically be moved five positions, and as substation No. 5 is the one selected, all of the pins 38' of the substations except the pin 38' in the substation No. 1, pass into the 120 groove 54 when the substation No. 5 is selected, while at substation No. 1, the pin 38' stands under the ridge *a*. Thus all of the pins 38' except the one at the calling substation No. 1 are caused to pass through the 125 respective spaces 55' and consequently enter the respective grooves 54, this being due to the fact that the receivers were upon the hooks and the spring 41' was permitted to elevate the shunt contacts 38 and 39, unhin- 130

dered by the electrical attraction of the magnet 47 upon the armature 41, which is connected to and forms a part of the swingingly mounted contacts 38 and 39. At this time, except at substation No. 1, the circuit to the magnet 47 was opened at contacts 61 and 62 and thus as before described, the spring 41' was permitted to cause the pin 38' to pass through the slot 55' above referred to.

In order to keep the calling substation instrument No. 1, from being shunted by the action of the disk 36, in such instrument when the disk was rotated, and at the time 15 substation No. 5 was selected by the exchange station, it will be observed that the receiver being from the hook in substation No. 1 will cause the closure at contacts 61 and 62 by the receiver hook 25, and thus a 20 circuit, as will presently appear, to the electromagnet 47 was closed, so as to attract the armature 41 and move the contacts 38 and 39 against the action of the spring 41', to cause the pin 38' to be prevented from entering the slot 55', thus causing the same to be held below ridge a as long as properly operated. Thus it will be seen that the calling substation can be placed in communication 25 with any of the substations controlled 30 from the exchange station, and that the shunt contacts or switch 38-39 will be opened at the calling substation No. 1 as the projection 38'' will ride upon the ridge a and thus open the shunt contacts 38 and 39 35 so that conductors 42-43 at the calling substation are connected to the line $L-L'$ as in my former Patent No. 1,061,285. Thus the calling substation will have its disk 36 in such position that the release of the selecting key K at the exchange station, as set forth in the above mentioned patent, will permit of the return of the disk 36 to zero 40 position, or to the position as shown in Fig. 8.

45 The zero position here termed and regarded as slot 60, is one step in advance of the normal position as shown in Fig. 8 of substation No. 1 and five positions in advance in all positions at substation No. 5 50 and so on. It will therefore be noted that the wedge shaped projection 38^a is placed upon and carried by the disk 36 at the substation No. 5, in the present instance the called substation, in such position as to open the 55 shunt contacts 38-39 and thus permit of the proper connection and signaling of the substation No. 5 for connection with substation No. 1.

Under normal conditions when the 60 conversation between substations No. 1 and No. 5 is at an end, the receivers in both substations will be placed upon the hook and central will then remove the calling plug 2 from the calling jack 17 and thus as set 65 forth in my Patent No. 1,061,286 permit the

automatic return of the selecting key at the exchange station, and the operation of all of the disks 36 to the position shown in Fig. 8 with all parties in normal or zero position and in position whereby any one of the substations may signal the exchange station.

Presuming that the party at substation No. 5 after the completion of the conversation left the receiver off of the hook 25, but that the party at substation No. 1 returned his receiver to the hook after such conversation, the actuation of the disk 36 to zero position due to the automatic return of the selecting key, would cause the shunt contacts 38 and 39 in the substation No. 1 to cause the pin 38' to move under the ridge a at the slot 60, due to the fact that when the receiver was placed upon the hook, it closed contacts 77 and 78 and consequently the circuit to the electromagnet 47, and when 85 the pin 37' passed the contacts 74 and 75 between the position No. 1 and zero upon the calling substation, or adjacent the slot 55, the electromagnet 47 was energized and thus attracted the armature 41 to cause the 90 shunt contacts 38 and 39 to follow the dotted position as illustrated in Fig. 17, at which time the shunt switch was permitted to open and thus permit the calling substation to be connected to the line for again signaling 95 the exchange station.

The pin 38' at the substation No. 5 due to the fact that the receiver was left off of the hook, was caused to pass from below the ridge 38^a, through the slots 55 and 57', 100 as the circuit to the electromagnet 47 in the substation No. 5 was not closed and therefore the shunt contacts 38 and 39 were moved by the spring 41' to assume the position as shown in dotted lines Fig. 11.

105 Should the substation No. 5 with the parts in the position here described, be selected or called by exchange, the receiver being off of the hook, and the shunt switch 38-39 being closed, the disk 36 would revolve and 110 when the pin 38' has reached tooth 38^a at position 60' of the disk, the shunt contacts 38 and 39 will be permitted to open due to the sliding of the contacts upon the tooth 38^a, at which time, the call-up alarm contacts 85 and 90 would be closed and thus 115 ring the alarm in the called substation No. 5, even though the receiver is not upon the hook and the hook 25 is elevated. This action will also cause the closing of the local 120 talking circuit at contacts 70 and 71, the circuit for which will be set forth later on. The contact 38 has a block of insulation that contacts the contacts 70-71, the same when open, as shown in Fig. 7, engaging 125 the contact 71 and moving it toward and into engagement with the contact 70. The subscriber at substation No. 5 observing the receiver to be off of the hook, will vibrate the hook, see Fig. 16, and as will presently 130

appear strikes the contact 86' to operate the pawl *d* and thus move the shunt contacts 38-39 from the groove 58 to below the ridge *a* of the disk 36, this action opening the contacts 86 and 90 and opening the circuit to the call-up alarm 81 and leaving the pin 38', to maintain the shunt switch 38-39 in substation No. 5 open with the contacts 70 and 71 closed. Thus it will be seen that when the pin 38' is traveling in the groove 54 and engages the tooth 38^a, at the substation called, the disk will be moved to position, as shown in Fig. 10, the switch 85 and 86 will be closed and the call-up alarm 15 will be energized to indicate to the called substation regardless of the position of the receiver hook that the calling substation is desired to be placed in communication therewith. It will thus be seen, that provision 20 is made for operating the call-up alarm switch 85, 86 and 90 regardless of the position of the receiver in the called substation so that such substation may be properly connected and communicated with when desired.

Should the party at substation No. 5 at any time place the receiver upon the hook, the next time that the exchange operator actuates the disk 36 so as to place the same 30 at zero position, the contacts 77 and 78 in substation No. 5, being closed by the hook 25, the electromagnet 47 would be energized due to the closure of the contacts 74 and 75 at the time the pin 37' on disk 36 passed the same, and as such action moved the contacts 38 and 39 in the substation No. 5 against the action of the spring 41', the adjustment of the block 40 by the armature 41 will cause the pin 38' to pass through the 40 openings 57' and 55 to assume the position below the ridge *a* at zero position, or as clearly shown in Fig. 13.

By referring to Figs. 8 through 17, the various conditions arising due to the position of the receiver upon the hook as regards the shunt switch 38 and 39 are clearly set forth, the position of the pin 38' in the various substations being as follows:

In Fig. 8, the disk 36 and pin 38' are in 50 normal shunt open position, and the same applies as in Fig. 9 when a substation is calling the exchange or central station.

In Fig. 10, the called substation has been selected, while in Fig. 11, the pin 38' is in 55 the position it assumes, if the substation fails to place the receiver upon the hook at the end of the conversation and the exchange operator has released the selecting key to return the disk 36 to normal position.

In Fig. 12, the pin 38' is in the position it would assume in the calling substation under the same conditions.

In Fig. 13, the pin 38' is in the position 65 it would assume which is the reverse of the

position 11 and 12 had the receiver been returned to the hook.

Fig. 14 shows the travel of pin 38' on disk 36 at all stations not selected where the receivers are properly placed on hooks.

In Fig. 15, the pin 38' is in the position with the contacts 38 and 39 opened it would assume had the receiver been left off the hook when selected and the substation selected by the exchange, while in Fig. 16 describes the pin 38' when the subscriber as in Fig. 15 has placed his receiver upon the hook after the conversation and the exchange has returned the pin to zero position.

In Fig. 17, is illustrated, the path of the pin 38' when a selected substation as in Fig. 10 was moved to zero position.

In Fig. 18 the contacts 38 and 39 are in normal or shunt open position; Fig. 19, the position of the contacts 38 and 39 closed in 85 an uncalled substation, is illustrated; Fig. 20 the contacts 38-39 are shown open in a selected or called substation; while in Fig. 21, the contacts 38 and 39 are closed and in the position they assume when a substation 90 leaves the receiver off the hook and is shunted from the line, the disk 36 being in normal or zero position.

The same action as regards the operation of the disk 36 is carried out in the installation as shown in Figs. 3 and 4, the only difference being that the magneto A is dispensed with and the alternating current call-up alarm generator G is installed at the exchange station E having the ground *g* at one 100 terminal while the other terminal is connected through the signaling device 9 to the line, so that when the hook 25 in the substation is elevated due to the receiver R being removed therefrom, said hook will engage the contact 150, and thus connect the conductor 151 and the ground *g'* to the line *L'* and thus cause the generator circuit with the exchange to be closed and the consequent energization of the signal 9 to indicate that a 110 substation is calling. By the insertion of the jack plug 1 in the answering socket 14 at the exchange station, the contacts 152 and 153 are opened and the current from the generator G is shunted through the opposite 115 coil of the signal 9 and grounded at *g* and thus entirely short circuited from the talking circuit so as not to interfere therewith during the selecting and connecting of a calling to a called substation.

When the call-up magneto A in substation No. 1 as before described was energized, the receiver being upon the hook, impulses were thrown upon the lines *L-L'* through the conductors 3 and 4, and the 120 condenser 6, said condenser being pervious to the magneto and to the talking current and impervious to the battery current, the magneto current flowing through the conductor 7 and the lines *L-L'* and the con- 125

130

ductor 8 to the exchange signal 9, which is connected to the conductor 10, closed by the contacts 11 and 12 and the conductor 13 to the line. Thus the exchange operator is notified that a substation desires to be communicated with, and the answering jack plug 1 is now inserted within the socket 14, so that the substation is connected for the transmission of speech to the calling substation. The 10 calling substation in the meantime having removed the receiver from the hook, has its transmitter T properly connected in the usual manner so that the subscriber may inquire of the exchange operator the selection 15 of a called substation. The answering jack socket 14 as illustrated in both diagrams in Figs. 1 and 3, is connected to the line L—L' through the conductors 15 and 16.

At this time, the exchange operator inserts the calling jack plug 2 in one of the calling sockets 17, which closes the contacts 18 and 19 at the calling socket, and thus connects the exchange so that by the manipulation of the selecting key K as particularly set forth in my Patents Nos. 1,061,285 and 1,061,286 to throw impulses upon the line from the battery 23 to energize all of the electromagnets 29 in every substation, thus imparting a proper step-by-step movement to the shafts 35 and the respective disks 36 and 37. This action will cause the proper manipulation of the shunt contacts 38 and 39, and the other contacts 44—45, 70—71 and 74 and 75, 85—86 and 90 so that the called substation will be connected to the line L—L' with the shunt contacts 38—39 open, while the uncalled substations will have the shunt contacts 38—38 held closed and thus be shunted from the line until the selecting key K at the exchange has been released due to the removal of the jack plug 2 from its socket 17 and the return to initial or zero position of the selecting key and consequently the step-by-step action imparted to the shafts 35 in all substations and the returning of the disks 36 and 37 to zero position so that all substations are again connected to the line for calling the exchange station.

50 The manipulation of the selecting key after the calling jack plug 2 is inserted in the socket 17, will cause the throwing upon the line of impulses from the battery 23 and to the electromagnets 29, each one of which is connected through the conductors 5 and 7 to the line L—L' in each substation. At this selecting key, in conjunction with the contacts 11 and 12, are the contacts 20 and 21, which are operated by the selecting key as before stated, the automatic opening and closing of the same connecting and disconnecting the battery 23 through the conductors 22, 24 and 24' to the line conductor L—L' and thus energizing all of the electromagnets 29.

When the receiver hook 25 is in its lowermost position, with the receiver R thereupon, the same completes the circuit with the line L' through the hook 25, the contact 26, the conductor 27, the bridging conductor 28, around the call-up magneto A, and the conductors 3, 4 and 5, the condenser 6, and the conductor 7 to the line L' at the opposite side of the substation.

When the various electromagnets 29 in all of the substations are simultaneously energized, the armatures 30 are attracted against the action of their respective springs 30', and operates the respective operating and arresting pawls 31—32, which in turn 80 actuate the respective operating and arresting ratchet wheels 33 and 34, keyed upon the rotatable shafts 35. Each shaft in the present instance is carried by a base B, which is adapted to seal the lower end of the 85 casing C of the desk instrument, as clearly shown in Fig. 5, said casing being so constructed as to permit of the easy introduction of the present substation device and the proper connection thereof so that the 90 receiver hook rod 25' will be in ready position to be moved into and out of engagement with the releasing pawl 86—86' which permits of the readjusting of the shunt contacts 38—39 when the subscriber at the substation has left the receiver from the hook and the same is called and the receiver is again placed upon the hook to establish the proper connection with the line. Thus the present device is readily installed and positioned 95 in place and due to the spring 41' and the electromagnet 47, the present mechanism may be operated regardless of the position of the desk instrument and this peculiar arrangement thus permitting the 100 same to be placed at any angle and be particularly carried bodily by a desk outfit.

When the shaft 35 has the step-by-step action imparted thereto, the disks 36 and 37 are operated, and the various or desired 110 operations controlled by said disks are carried out.

As before described, the shunt controlling contacts 38 and 39 are operated by the peripheral portion of the disk 36, the pin 38' 115 thereof being adapted to follow the dotted position, as illustrated in Fig. 8 through 16 and thus consequently controlling the shunt contacts 38 and 39 according to the position of the receiver hook 25 and the receiver R 120 in the substations.

Disposed in the path to be engaged by the pin 37' of the disk 37, are two sets of contacts 44 and 45, and 74 and 75, the contact 44 having led therefrom, a conductor 46, 125 which is connected to the receiver hook 25 at the contact 61, the receiver hook being disposed to bridge the contacts 61 and 62, and thus complete the circuit through the conductor 48, the electromagnet 47, the con- 130

ductor 51, the battery 65, the conductor 53, and the contact 45. Disposed to actuate the armature 41 at the block 40, which is shifted so as to permit of the swinging of the contacts 38 and 39 and also contacts 70 and 71 and 85 and 86, transversely of the peripheral edge of the disk 36, so that said contacts 38 and 39 may be controlled for separation or engagement, according to the desired condition, the circuit and the electromagnet 47 is provided to move the same in one direction while the spring 41' moves it in the opposite direction.

The contacts 61 and 62 are disposed to be bridged by the receiver hook 25, as are also the contacts 49 and 50, the closure of the contacts 61 and 62, causing the energization of the electromagnet 47 at the time the pin 37' is passing the contacts 44 and 45, as will presently appear, the same as before stated, occurring when the receiver R is raised from the hook 25 and the hook is permitted to elevate and thus close contacts 61-62. The energization of the electromagnet 47 will attract the armature 41 and cause the movement of the shunt contacts 38 and 39 in opposition to the spring 41' and will place the said contacts with the pin 38' below the ridge *a* so that the contacts 38-39 are permitted to open and the substation is thus connected to the line.

As before stated, the periphery of the disk 36 is so mutilated or constructed as to provide the three circumferential ridges *a*, *b* and *c*, and to define the two grooves 54 and 58, the disk 36 also carrying the tooth 38^a which is placed at position 60' as before set forth. The ridge *a* which is the lowermost ridge of the disk is provided with the slot 55-55' to form a connection or communication with the recess or groove 54 and thus allow the means for permitting the pin 38' to move from below the ridge *a* into such recess 54. The ridge *b* is provided with a slot 57' which permits the introduction or movement of the pin 38' into the recess 58 all of which actions are due to the movement of the spring 41' when the disk 36 is rotated and the electromagnet 47 is not energized. When the pin 38' is in position 60', the contacts 85-86 and 90 of the call-up alarm 81, as well as the contacts 70-71 are closed, thus ringing the call-up alarm at the selected substation. The pin 38' when passing through the grooves or slots 55-55' causes the contacts 38-39 to be moved transversely of the periphery of the disk 36, and as the ridge *b* is provided with the slot 57' as before stated, the pin 38' is permitted to enter the groove 58 adjacent the ridge *c*.

As may be found necessary and expedient, the disk 36 may be provided with any number of teeth 38^a, this being regulated according to the number of substations employed, and each of said teeth as before described,

provides means for the control of the contacts 38-39, 70-71, and 85, 86 and 90, so that the same may be properly opened and closed for connecting a called substation to a calling substation, or for shunting all except such calling and called substations from the line, the ridges *a* in all of the substations being so designed as to prevent the closure of the contacts 38 and 39 of the calling and the called substations. 75

In order to provide a means for properly connecting the transmitter T to the line, the two contacts 49 and 50 are disposed in the path to be bridged by the receiver hook 25, when the hook is elevated, the circuit thus formed comprising the conductor 64, the battery 65, the conductor 66, the transmitter T, the conductor 67, the induction coil 68, the conductor 69, the closed contacts 70 and 71, controlled by the shunt contacts 38 and 39, the conductor 63 and the contact point 50.

The contacts 70 and 71 are so disposed with relation to the shunt contacts 38-39, that the same will be open when the contacts 38 and 39 are closed, thus permitting the opening of the local battery circuit so that the manipulation of the hook 25 to elevated position will not cause the closure of such local battery circuit it being necessary that 95 the contacts 38 and 39 be opened to permit the closure of the contacts 70 and 71 and thus properly connect the local battery circuit so that when the receiver hook 25 in the called or selected substation is elevated, the local battery circuit will be connected to the line, except, when the pin 38' is standing in the groove 58 at zero or normal position. 100

The two spring contacts 74-75, which are controlled by the pin 37' and are connected by means of the contacts 77-78, bridged by the receiver hook 25, at the time when the receiver hook is depressed and the receiver is thereupon, will close the circuit to the electromagnet 47 through the conductor 51', the electromagnet 47, the conductor 51, the battery 65, the conductor 65^a, the contacts 74 and 75, and the conductor 65^b to the contact 78, this circuit providing means for returning the pin 38' to the proper groove of the disk 36. When such calling substation has completed the conversation with the called substation, the receiver R is placed upon the hook and the selecting key K at the exchange station has been manipulated by the removal of the calling plug 2 as before described, the disks 36 and 37 will be returned to initial or zero position and thus rotate the respective shafts 35 in all of the substations. This same condition is employed to return the pin 38' upon the groove 54, through the slot or recesses 57' or 55, when a party using an instrument has neglected to place the receiver upon the hook at the 115 120 125 130

completion of the conversation, the spring 41' at this time having pushed the pin 38' from the groove 54 to the groove 58, after the exchange operator has disconnected the calling substation by the return to normal position of the selecting key K.

The contacts 77 and 78 have also provided a means for connecting the call-up alarm 81 at the substation, so that when the disk 36 is operated and causes the closure of contacts 85 and 86, the call-up alarm 81 will be energized through the following circuit: The receiver hook 25, the contact 78, the conductor 80, the call-up alarm 81, the conductor 82, the battery 65, the conductor 64, the conductor 84, the contact 86, the contact 85, the conductor 87 and the contact 77. Thus the call-up alarm will be energized and will remain energized until the receiver is removed from the hook to permit the elevation of the same and the opening of the call-up alarm circuit at contacts 77-78, or as particularly set forth in my co-pending application filed April 9, 1912, Serial No. 690,014, renewed August 20, 1913, Serial No. 785,818, the said alarm in this instance as herein noted, being controlled by the local battery or a battery at the substation and being so constructed as to prevent the manipulation thereof accidentally caused by the engagement of the tooth 38^a when returning the disk 36 to zero position.

Should the subscriber at the called substation for any reason have left the receiver R off of the hook, the hook 25 will thus be elevated and the circuit to the call-up alarm 81 at contacts 77 and 78 will be open, but when the disk 36 has been rotated through the selecting key from the exchange station, just as the pin 38' reaches a position approximately at zero or initial position, the spring 41', not being opposed by the electromagnet 47, will cause the pin 38' to pass through the recesses 55 and 57, or as clearly illustrated in Fig. 11 so that the next time that the substation is called by the exchange station, the pin 38' owing to the party not placing the receiver upon the hook, will be caused to travel in the groove 58, so that when the pin 38' arrives at the tooth 38^a, the contacts 38-39 will open, and the contacts 85 and 90 will close so that the call-up alarm 81 will be energized through the following circuit: The contact 90, the conductor 91, the alarm 81, the conductor 82, the battery 65, the conductor 64, the conductor 84, and the contact 86. Thus it will be seen that the alarm 81 will continue to ring similarly to the before mentioned ringing when the receiver was on the hook, thus providing a means for the calling of a substation regardless of the position of the receiver hook.

The contacts 86 and 90 are operated by the spring contact 85, disposed over the contact 38 of the shunt connection, so that when

the shunt connection is closed at contacts 38 and 39, the contacts 85, 86 and 90 will be opened, except when the pin 38' is standing in the groove 58 at position 60'. Thus the uncalled substations will be shunted from the line and will also have the circuit controlling the call-up alarm open, especially at contacts 86 and 90, so that such call-up alarm circuit cannot be operated until the shunt contacts 38 and 39 are opened.

The rod 25' which as shown in Fig. 5 is mounted for vertical sliding movement within the standard of the desk outfit, has its end 25'' so disposed, that when the receiver R is placed upon the hook 25, the rod will move downwardly and cause the pawl 86' to adjust contacts 38 and 39 from the groove 58 to the groove 54, the same action of the receiver rod thus placing the contacts 38-39 in position 60'.

When the receiver has been left from the hook, the pin 38' is pushed to the groove 58 by the spring 41' as just described, and the contacts 38-39 will cause the opening of the talking circuit at 70-71 and the alarm circuit at contacts 85 and 90.

The party wishing to call the exchange station observing the mistake that the receiver has been left from the hook and the pin 38' at this time being in the groove 58 at zero position, said party will vibrate the hook and consequently the rod 25' so that the tooth 86' will operate the pawl d, placing the pin 38' below ridge a and thus separating the contacts 38 and 39 and connecting the substation directly to the talking circuit. If such substation is called when the receiver is thus being adjusted, the disk 36 and contacts 85 and 90 will be moved and the pin 38' will be placed at position 60' of the disk and the call-up alarm circuit will be closed while the talking contacts 70 and 71 of the shunt contacts 38 and 39 will be opened.

In Figs. 24 and 25, the pawl 86' is a curved plate mounted for sliding movement upon and carried by the disk 36. The hook rod engaging end e is pivoted for lateral movement so that any fixed portion of the lock-out device struck the end 25'' of the rod 25' during the rotation of the disk 36 will not slide the pawl. The beveled end f however, when engaged by the end 25'' of the rod 25' when the rod is lowered, imparts sliding movement to the pawl 86' against the action of the spring g' so that the free end of the pawl 86' will engage the upper edge of the contact 38 and thus push said contact 38 and contact 39 from the position as shown in Fig. 21 to that shown in Fig. 18.

In Figs. 26 and 27, the pawl 86^a, is mounted upon the disk 36 for vertical swinging and longitudinal sliding movements, by means of its stem h, and the sleeve j. The upturned end k is held by the spring l in the path to be depressed by the end 25'' of the rod 25'.

Disposed in the exchange station for the actuation of the electromagnet 99 of the selecting key, said electromagnet controlling the armature 99' and as particularly set forth in Patent No. 1,061,286, are the contacts 95 and 96 which are closed by the barrel of the selecting key K, such closure closing the circuit including the battery 93, the conductor 94, the contacts 95 and 96, the conductors 97 and 98, the electromagnet 99 and the conductor 100. This action controls the armature 99' so that the carriage may be moved to the desired position. The contacts 101-102 are disposed in the path to be actuated by the carriage of the selecting key and connect through the medium of the conductor 103, the normally closed contact 104 of the calling socket 17 through the conductor 105 which is connected to the normally closed contact 106 of the answering socket 14 and the conductor 107 with the battery 93. The circuit being accomplished through the conductor 100, the electromagnet 99, the conductor 98, the conductor 97 and 96 and 101 and 102 control the energization of the electromagnet 99.

In order to provide a signaling means at each substation so as to indicate when the line is busy, a segmental ridge 155 is carried by the disk 37 keyed upon the upper end of the shaft 35 and disposed in the path of this segmental ridge 155, is a pair of spring contacts 157 and 158, which constitute the switch for the circuit including such contacts, the conductor 159, the battery 160, the signal light 161, and the conductor 162. Thus at any position except zero position, the switch is closed and the signal light energized, the recess formed by the mutilation of the ridge 155 causing the opening of the switch and this action being at zero position.

This signal light is of an exceedingly low voltage, and is disposed within the casing C and readily observable through the observation aperture formed therein.

In order to provide a means, whereby a conversation may be recorded, especially in the case where the called subscriber is absent, a talking machine M, either in the form of a mechanical machine as the dictaphone or the telephone may be employed, the circuit for controlling the starting and stopping of the same being actuated by the pin 37^a of the disk 37 through the switch 163-164 which is only permitted to be closed when the receiver is off of the hook, the subscriber notifying the exchange before doing so, so that the exchange when calling the subscriber or connecting him to a calling substation can notify the calling substation that the party is absent but that the recording machine can be connected so that the message may be impressed there-

upon either mechanically as in the dictaphone or electrically as in the telephone.

This circuit includes the clutch mechanism 165, controlled by the electromagnet 166, the conductor 167, the battery 160 and the contracts 163-164.

Where the telephone is employed, the record is recorded magnetically upon a magnetizable wire, or where the dictaphone is employed, the usual wax cylinders may be employed, and constructed so that several in succession may be connected to record a complete message or messages.

Where the telephone is employed, the coil for recording the message is connected directly to the talking circuit and thus is in series or multiple with the receiver R while where the dictaphone is employed, the receiver may be positioned when removed from the hook directly in the horn thereof, the present invention residing in the fact that the control of the telephone or dictaphone when the receiver is from the hook is automatic and actuated by the shaft 35 which carries the disks 36 and 37.

A light wire X, that carries a very small amperage as for instance, the talking current of 24 volts and 2 amperes is employed to form a path for the talking current and thus assists in preventing the actuation of the electromagnet 29 by the talking current when the exchange operator has connected the talking circuit to the line. In fact any means that will form the desired path for the talking current may be used. It will be noted that the electromagnet 29 is connected to the line at all times even though the shunt contacts 38 and 39 would be closed. The battery 23 will intermittently energize the electromagnet 29 when the contacts 38 and 39 are closed, through the following circuit: the battery 23, the conductor 24, the line L', the conductor 43, contacts 38 and 39, the conductor 42, the conductor 4, the conductor 4', the electromagnet 29, the conductors 7' and 7, the continuation of the line L'-L, the conductor 24', the contacts 20 and 21, and the battery 22.

Therefore as the battery is connected to the line, its amperage being greater or having different characteristics than the talking battery, will energize the electromagnet 29 and step the shaft 35.

In the magneto call systems as shown in Figs. 1 and 2, in order to prevent the subscriber from removing the receiver and permitting the elevation of the hook 25, without ringing the magneto, an armature lock 168, is provided to normally seat in a recess in the rod 25', and hold the same in lowermost position. In order to provide a release for the lock 168, an electromagnet 169, by means of the conductors 170 and 171 is connected to receive current from the

- magneto, which is operated after the calling subscriber has raised the receiver or released it from the hook 25. Thus the operation of the magneto to signal the exchange station also energizes the electromagnet 169, which attracts the armature lock 168 to release the rod 25' and hook 25 to its usual spring. Thus the subscriber must operate the magneto to signal the exchange. In order to release the lock 168, when the substation is selected, the pins 172, are disposed to engage the lock 168 mechanically and move it to disengage the rod 25'.
- 15 As the exchange at night is not called so frequently as during the day time, the night bell or signal 174, controlled by the signal and contact 173 to receive current from the alternating current generator G, at the exchange station is provided.

20 The arrangement here shown and described provides for the shunt contacts, 38-39 to contact the contacts 70-71 and all of the others associated therewith as illustrated in Fig. 7. This feature is not shown in my former Patents No. 1,061,285 and No. 1,061,287.

25 What is claimed is:

- 30 1. In a selective system of telephony, the combination of an exchange station and a plurality of substations connected electrically for the transmission of intelligence, said exchange station having a selecting device, and each substation having a receiver, a battery, a local circuit including the battery, a transmitter in said local battery circuit, a shunt connection with the line provided with a switch, an electro-magnet influenced by the selecting device, means controlled by the electro-magnet for opening and closing the switch of the shunt connection, and a switch in the local battery circuit controlled by the shunt connection switch, whereby the local battery circuit is open when the shunt is closed, and vice versa.

- 35 2. In a selective system of telephony, the combination of an exchange station and a plurality of substations connected electrically for the transmission of intelligence, said exchange station having a selecting device, and each substation having a receiver, a battery, a local circuit including the battery, a transmitter in said local battery circuit, a shunt connection with the line provided with a switch, an electro-magnet influenced by the selecting device, means controlled by the electro-magnet for opening and closing the switch of the shunt connection, a switch in the local battery circuit controlled by the shunt connection switch, whereby the local battery circuit is open when the shunt switch is closed, and vice versa, a call-up alarm, a circuit including said battery and the call-up alarm, and a switch in the last circuit controlled by the

40 shunt connection switch, the same being opened when the shunt connection is closed, and vice versa.

45 3. In a selective system of telephony, the combination of an exchange station and a plurality of substations connected electrically for the transmission of intelligence, said exchange station having a selecting device, and each substation having a receiver, a battery, a local circuit including the battery, a transmitter in said local battery circuit, a shunt connection with the line provided with a switch, an electro-magnet influenced by the selecting device, means controlled by the electro-magnet for opening 50 and closing the switch of the shunt connection, a switch in the local battery circuit controlled by the shunt connection switch, whereby the local battery circuit is open when the shunt switch is closed, and vice 55 versa, and means controlled by the electro-magnet for regulating the position of the shunt connection switch relatively to the controlling means thereof, and whereby the shunt connection switch may be operated 60 when the receiver is upon, or off, its hook.

55 4. In a selective system of telephony, the combination of an exchange station and a plurality of substations connected electrically for the transmission of intelligence, 65 said exchange station having a selecting device, and each substation having a receiver, a battery, a local circuit including the battery, a transmitter in said local battery circuit, a shunt connection with the line provided with a switch, an electro-magnet influenced by the selecting device, an intermittently operable means controlled by the electro-magnet for opening and closing the switch of the shunt connection, and a switch 70 in the local battery circuit controlled by the shunt connection switch, whereby the local battery circuit is open when the shunt switch is closed, and vice versa.

60 5. In a selective system of telephony, the combination of an exchange station and a plurality of substations connected electrically for the transmission of intelligence, said exchange station having a selecting device, and each substation having a receiver, a battery, a local circuit including the battery, a transmitter in said local battery circuit, a shunt connection with the line provided with a switch, an electro-magnet influenced by the selecting device, an intermittently operable means controlled by the electro-magnet for opening and closing the switch of the shunt connection, a switch in the local battery circuit controlled by the shunt connection switch, whereby the local 75 battery circuit is open when the shunt switch is closed, and vice versa, a call-up alarm, a circuit including said battery and the call-up alarm, and a switch in the last circuit controlled by the shunt connection 80

85 110 115 120 125 130

switch, the same being closed when the shunt connection is opened, and vice versa.

6. In a selective system of telephony, the combination of an exchange station and a plurality of substations connected electrically for the transmission of intelligence, said exchange station having a selecting device, and each substation having a receiver, a battery, a local circuit including the battery, a transmitter in said local battery circuit, a shunt connection with the line provided with a switch, an electro-magnet influenced by the selecting device, an intermittently operable means controlled by the electro-magnet for opening and closing the switch of the shunt connection, a switch in the local battery circuit controlled by the shunt connection switch, whereby the last local battery circuit is open when the shunt switch is closed, and vice versa, and means controlled by the electro-magnet for regulating the position of the shunt connection switch relatively to the controlling means thereof and whereby the shunt connection switch may be operated when the receiver is on, or off, its hook.

7. In a selective system of telephony, the combination of an exchange station and a plurality of substations connected electrically for the transmission of intelligence, said exchange station having a selecting device, and each substation having a receiver, a receiver hook, a battery, a local circuit including the battery, a transmitter in said local battery circuit, a shunt connection with the line provided with a switch, an electro-magnet influenced by the selecting device, a step-by-step device controlled by the electro-magnet for opening and closing the switch of the shunt connection, and a switch in the local battery circuit controlled by the shunt connection switch, whereby the local battery circuit is open when the shunt switch is closed, and vice versa.

8. In a selective system of telephony, the combination of an exchange station and a plurality of substations connected electrically for the transmission of intelligence, said exchange station having a selecting device, and each substation having a receiver, a receiver hook, a battery, a local circuit including the battery, a transmitter in said local battery circuit, a shunt connection with the line provided with a switch, an electro-magnet influenced by the selecting device, a step-by-step device controlled by the electro-magnet for opening and closing the switch of the shunt connection, a switch in the local battery circuit controlled by the shunt connection switch, whereby the local battery circuit is open when the shunt switch is closed, and vice versa, a call-up alarm, a circuit including said battery and the call-up alarm, and means controlled by the shunt connection switch, the

same being closed when the shunt connection is opened, and vice versa.

9. In a selective system of telephony, the combination of an exchange station and a plurality of substations connected electrically for the transmission of intelligence, said exchange station having a selecting device, and each substation having a receiver, a receiver hook, a battery, a local circuit including the battery, a transmitter in said local battery circuit, a shunt connection with the line provided with a switch, an electro magnet influenced by the selecting device, a step-by-step device controlled by the electro-magnet for opening and closing the switch of the shunt connection, a switch in the local battery circuit controlled by the shunt connection switch, whereby the local battery circuit is open when the shunt is closed and vice versa, and means controlled by the electro magnet and simultaneously with the shunt switch controlling means for regulating the position of the shunt connection switch relatively to the controlling means thereof, and whereby the shunt connection switch may be operated when the receiver is upon, or off, its hook.

10. A substation, including a shunt connection with the line, a switch in said connection, a battery, a circuit including said battery, a transmitter in said circuit, a receiver, a receiver hook, said receiver hook being disposed to bridge said circuit when elevated, a switch in said circuit controlled by the switch of the shunt connection, such switch being open when the shunt switch is closed and vice versa, and means influenced from the line for operating the shunt switch.

11. A substation, including a shunt connection with the line, a switch in said connection, a battery, a circuit including said battery, a transmitter in said circuit, a receiver, a receiver hook, said receiver hook being disposed to bridge said circuit when elevated, a switch in said circuit controlled by the switch of the shunt connection, such switch being open when the shunt switch is closed and vice versa, a call-up alarm, a switch, a circuit including said battery, the last switch and the call-up alarm, and means influenced from the line for operating the shunt switch and the call-up alarm switch.

12. A substation, including a shunt connection with the line, a switch in said connection, a battery, a circuit including said battery, a transmitter in said circuit, a receiver, a receiver hook, said receiver hook being disposed to bridge said circuit when elevated, a switch in said circuit controlled by the switch of the shunt connection, such switch being open when the shunt switch is closed and vice versa, a call-up alarm, a switch, a circuit including said battery, the last switch and the call-up alarm, and means in-

fluenced from the line for operating the shunt switch and the call-up alarm switch, the receiver hook, when the receiver is thereupon, being a bridge in the call-up alarm circuit, whereby the call-up alarm circuit is open when the receiver is removed.

13. A substation, including a shunt connection, receiver is removed.

substation, including a shunt connection with the line, a switch in said connection, a battery, a circuit including said bat-

10 tery, a battery, a circuit including said battery, a transmitter in said circuit, a receiver, a receiver hook, said receiver hook being disposed to bridge said circuit when elevated, a switch in said circuit controlled by the switch of the shunt connection such

15 of the switch of the shunt connection, such switch being open when the shunt switch is closed and vice versa, a call-up alarm, a switch, a circuit including said battery, the last switch and the call-up alarm, means influenced from the line for operating the

20 shunt switch and the call-up alarm switch, the receiver hook, when the receiver is there-
upon, being a bridge in the call-up alarm circuit, whereby the call-up alarm circuit is
25 open when the receiver is removed, and

25 means for controlling the shunt switch, whereby when the receiver is off the hook the call-up alarm circuit may be energized.

14. A substation, including a shunt connection with the line, a switch in said connection, a battery, a circuit including said battery, a transmitter in said circuit, a receiver, a receiver hook, said receiver hook being disposed to bridge said circuit, -

35 being disposed to bridge said circuit when elevated, a switch in said circuit controlled by the switch of the shunt connection, such switch being open when the shunt switch is closed and vice versa, a call-up alarm, a switch, a circuit including said battery, the

40 switch, a circuit including said battery, the last switch, and the call-up alarm, means influenced from the line for operating the shunt switch and the call-up alarm switch, the receiver hook, when the receiver is thereupon, being a bridge in the call-up alarm

open, being a bridge in the call-up alarm circuit, whereby the call-up alarm circuit is open when the receiver is removed, means for controlling the shunt switch, whereby when the receiver is off the hook, the call-up alarm circuit may be energized, and

50 A similar circuit may be energized, and means controlled by the receiver hook for operating the shunt switch to open the call-up alarm circuit after the last circuit has been thus energized.

15. A substation, including a shunt connection with the line, an oscillatory switch in said connection, a battery, a circuit including said battery, a transmitter in said circuit, a receiver, a receiver hook, said receiver hook being disposed to bridge the circuit when elevated, a switch in said circuit controlled by the switch of the shunt connection, such switch being open when the shunt switch is closed and vice versa, means having a plurality of switch controlling means influenced from the line for operating the shunt switch, and a spring and

electromagnetically actuated means controlled by said last means for oscillating the shunt switch to select a controlling means therefor.

16. A substation, including a shunt connection with the line, an oscillatory switch in said connection, a battery, a circuit including said battery, a transmitter in said circuit, a receiver, a receiver hook, said receiver hook being disposed to bridge the circuit when elevated, a switch in said circuit controlled by the switch of the shunt connection, such switch being open when the shunt switch is closed and vice versa, a call-up alarm, a switch, a circuit including said battery, the last switch, and the call-up alarm, means influenced from the line for operating the shunt switch and the call-up alarm switch, and a spring and electromagnetically actuated means controlled by said last means for oscillating the shunt switch to select a controlling means therefor. 70 75 80 85

17. A substation, including a shunt connection with the line, an oscillatory switch in said connection, a battery; a circuit including said battery, a transmitter in said circuit, a receiver, a receiver hook, said receiver hook being disposed to bridge the circuit when elevated, a switch in said circuit controlled by the switch of the shunt connection, such switch being open when the shunt switch is closed and vice versa, a call-up alarm, a switch, a circuit including said battery, the last switch, and the call-up alarm, means influenced from the line for operating the shunt switch and the call-up alarm switch, and a spring and electromagnetically actuated means controlled by said last means for oscillating the shunt switch to select a controlling means therefor, the receiver hook, when the receiver is thereupon, being a bridge in the call-up alarm circuit, whereby the call-up alarm circuit is open when the receiver is removed. 105

18. A substation, including a shunt connection with the line, an oscillatory switch in said connection, a battery, a circuit including said battery, a transmitter in said circuit, a receiver, a receiver hook, said receiver hook being disposed to bridge the circuit when elevated, a switch in said circuit controlled by the switch of the shunt connection, such switch being open when the shunt switch is closed and vice versa, a call-up alarm, a switch, a circuit including said battery, the last switch, and the call-up alarm, means influenced from the one for operating the shunt switch and the call-up alarm switch, and a spring and electromagnetically actuated means controlled by said last means for oscillating the shunt switch to select a controlling means therefor, the receiver hook, when the receiver is thereon, being a bridge in the call-up alarm circuit, whereby the call-up alarm circuit is 130

open when the receiver is removed, one of the plurality of means for controlling the shunt switch permitting the call-up alarm circuit to be energized when the receiver is off the hook.

19. A substation, including a shunt connection with the line, an oscillatory switch in said connection, a battery, a circuit including said battery, a transmitter in said circuit, a receiver, a receiver hook, said receiver hook being disposed to bridge the circuit when elevated, a switch in said circuit controlled by the switch of the shunt connection, such switch being open when the shunt switch is closed and vice versa, a call-up alarm, a switch, a circuit including said battery, the last switch, and the call-up alarm, means influenced from the line for operating the shunt switch and the call-up alarm switch, a spring and electromagnetically actuated means controlled by said last means for oscillating the shunt switch to select a controlling means therefor, the receiver hook when the receiver is thereupon, being a bridge in the call-up alarm circuit, whereby the call-up alarm circuit is open when the last circuit has been thus energized.

20. A substation, including a shunt connection with the line, a swingingly mounted switch in said connection, a battery, a circuit including said battery, a transmitter in said circuit, a receiver, a receiver hook, a rod carried by the hook, said receiver hook being disposed to bridge the circuit when elevated, a switch in said circuit controlled by the switch of the shunt connection, such switch being open when the shunt is closed and vice versa, a rotary disk having a plurality of selective switch controlling means, means for actuating the disk, from a distant point, and means for operating and swinging the shunt switch to place the switch in selected position relatively to the switch controlling means of the disk.

21. A substation, including a shunt connection with the line, a swingingly mounted switch in said connection, a battery, a circuit including said battery, a transmitter in said circuit, a receiver, a receiver hook, a rod carried by the hook, said receiver hook being disposed to bridge the circuit when elevated, a switch in said circuit controlled by the switch of the shunt connection, such switch being open when the shunt switch is closed and vice versa, a call-up alarm, a switch, a circuit including said battery, the last switch, and the call-up alarm, and means influenced from the line for operating the shunt switch and the call-up alarm switch, said last means having a plurality of selective switch swinging means con-

trolled from the line or by the receiver hook 85 rod.

22. A substation, including a shunt connection with the line, a swingingly mounted switch in said connection, a battery, a circuit including said battery, a transmitter in said circuit, a receiver, a receiver hook, a rod carried by the hook, said receiver hook being disposed to bridge the circuit when elevated, a switch in said circuit controlled by the switch of the shunt connection, such switch 75 being open when the shunt switch is closed and vice versa, a call-up alarm, a switch, a circuit including said battery, the last switch, and the call-up alarm, means influenced from the line for operating the shunt switch and the call-up alarm switch, said last means having a plurality of selective switch swinging means controlled from the line or by the receiver hook rod, the receiver hook when the receiver is thereupon, being 80 a bridge in the call-up alarm circuit, whereby the call-up alarm circuit is open when the receiver is removed.

23. A substation, including a shunt connection with the line, a swingingly mounted 90 switch in said connection, a battery, a circuit including said battery, a transmitter in said circuit, a receiver, a receiver hook, a rod carried by the hook, said receiver hook being disposed to bridge the circuit when elevated, 95 a switch in said circuit controlled by the switch of the shunt connection, such switch being open when the shunt is closed and vice versa, a call-up alarm, a switch, a circuit including said battery, the last switch, and the 100 call-up alarm, means influenced from the line for operating the shunt switch and the call-up alarm switch, said last means having a plurality of selective switch swinging means controlled from the line or by the receiver hook rod, the receiver hook when the receiver is thereupon being a bridge in the call-up alarm circuit, whereby the call-up alarm circuit is open when the receiver is removed, one of the plurality of selective 105 switch swinging means for controlling the shunt switch permitting the call-up alarm circuit to be energized when the receiver is off the hook.

24. A substation, including a shunt connection with the line, a swingingly mounted switch in said connection, a battery, a circuit including said battery, a transmitter in said circuit, a receiver, a receiver hook, a rod disposed to bridge the circuit when elevated, 120 a switch in said circuit controlled by the switch of the shunt connection, such switch being open when the shunt switch is closed and vice versa, a call-up alarm, a switch, a circuit including said battery, the last 125 switch, and the call-up alarm, means influenced from the line for operating the shunt switch and the call-up alarm switch,

said last means having a plurality of selective switch swinging means controlled from the line or by the receiver hook rod, the receiver hook when the receiver is thereupon 5 being a bridge in the call-up alarm circuit, whereby the call-up alarm circuit is open when the receiver is removed, one of the plurality of selective switch swinging means for controlling the shunt switch permitting 10 the call-up alarm circuit to be energized when the receiver is off the hook, the receiver hook rod being controlled by the receiver hook for operating the shunt switch to open the call-up alarm circuit after the 15 last circuit has been thus energized.

25. In a selective telephone system, an exchange station and a plurality of substations connected electrically for the transmission of intelligence, each substation including a 20 tubular support, a casing carried at the lower end thereof, a receiver hook mounted in said support, a rod carried thereby and extending through the tubular support into the casing, and a lock-out device insertible 25 within the casing and having a base sealing the same.

26. In a selective system of telephony, the combination of an exchange station and a plurality of substations connected electrically for the transmission of intelligence, 30 said exchange station having a selecting device, and each substation having an electro-magnetically actuated shunting device, a transmitter, a receiver, a receiver hook, a receiver hook lock normally locking the hook when the receiver is thereupon, a call-up 35 magneto, an electro-magnet in circuit with the magneto for releasing the lock when the

substation is signaling the exchange, and means for mechanically releasing the lock 40 operated by the shunting device as the substation is selected from the exchange station.

27. In a selective telephone system, an exchange station having a selective device, a plurality of substations, a receiver hook in 45 each substation, a rod depending therefrom, a resilient lock in the path thereof to engage the rod and lock the hook against elevating, a magneto at the substation, and an electro-magnet in circuit with the magneto and for 50 operating the lock to release the rod and hook.

28. In a selective telephone system, the combination of an exchange station having a selecting device, and a plurality of sub-stations connected electrically with the exchange station, each of said sub-stations having a step-by-step device, a sound recording mechanism, a releasing device for the sound record mechanism biased in one direction, 55 an operating device for the releasing device including an electro-magnet, a switch disposed in the path to be engaged by the step-by-step device, and a circuit including a source of electrical energy, said switch and 60 said electro-magnet, whereby when the circuit is energized the releasing device is operated against its bias.

In testimony that I claim the foregoing as my own, I have hereto affixed my signature in the presence of two witnesses. 70

RUBEN C. M. HASTINGS.
